(57) **CLAIM**

The ornamental design for a motorized fishing reel assembly, as shown and described.

DESCRIPTION

FIG. 1 is a rear isometric view of a motorized fishing reel assembly according to the present invention.

FIG. 2 is a front isometric view of the motorized fishing reel assembly shown in FIG. 1.

FIG. 3 is a right side view of the motorized fishing reel assembly shown in FIG. 1.

FIG. 4 is a left side view of the motorized fishing reel assembly shown in FIG. 1.

FIG. 5 is a front elevation view of the motorized fishing reel assembly shown in FIG. 1.

FIG. 6 is a rear elevation view of the motorized fishing reel assembly shown in FIG. 1.

FIG. 7 is a bottom plan view of the motorized fishing reel assembly shown in FIG. 1; and,

FIG. 8 is a top plan view of the motorized fishing reel assembly shown in FIG. 1.

The broken lines illustrate portions of an exemplary reel and an exemplary rod which are environmental and form no part of the claimed design.
